UNITED STATES PATENT OFFICE.

SAMUEL V. ESSICK, OF BROOKLYN, NEW YORK.

PRINTING-TELEGRAPH.

SPECIFICATION forming part of Letters Patent No. 443,135, dated December 23, 1890.

Application filed March 10, 1890. Serial No. 343,272. (No model.)

To all whom it may concern.

Be it known that I, SAMUEL VAN BUREN ESSICK, a citizen of the United States, residing at Brooklyn, county of Kings, and State 5 of New York, have made a new and useful invention in Printing-Telegraphs, of which the following is a specification.

My invention relates particularly to improvements in printing-telegraph receivers 10 of the page type, in which the message is printed upon a page or sheet of paper, after the manner of a type-writer, and is directed to improvements upon the receiving apparatus disclosed in my prior application for a patent, 15 Serial No. 290,247, filed in the United States Patent Office on the 7th day of November, 1888; and its objects are, first, to devise a receiving apparatus in which the paper-carriage shall be positively propelled through the 20 agency of a spring or weight impelled mechanism; second, to provide improved means for returning the paper-carriage to its normal position at any portion of its forward advancement, thereby avoiding the necessity of advancing said carriage to its extreme limit before it is returned to its normal position; third, 25 to cause the printing to be effected through the agency of power-impelled mechanism controlled by an escapement; and, fourth, the general accomplishment of the several functions 30 attributed to the entire mechanism hereinafter described. I accomplish these objects by the mechanism disclosed in the following application and illustrated in the drawings here- 35 with, but particularly pointed out in the claims which follow this specification.

Referring to the drawings, in which like letters of reference represent like parts wherever used, Figure 1 is a plan view of the entire apparatus. Fig. 2 is an end elevational view of the apparatus, as seen looking at Fig. 1 from right to left. Fig. 3 is an elevational view of the paper-carriage and its connections as seen looking at Fig. 1 in the direction of the arrow A⁴. Fig. 4 is a detail elevational view of the several levers and their connections for effecting the printing, the unison of the type-wheel, and the restoration of the paper-carriage to its normal condition 45 at any portion of its path, the several shafts and printing-lever, together with their sup-

ports, being shown in cross-sections. Fig. 5 is a cross-sectional view of Fig. 1, taken on line x x, as seen looking from right to left. Fig. 6 is a detail elevational view, partly in section, of a part of the releasing apparatus for releasing the paper-carriage both at the end of its excursion and during any portion of its journey. Fig. 7 is a sectional view, partly in elevation, of the paper-carriage and mechanism for feeding the paper forward line by line at the end of each excursion of the carriage. Fig. 8 is a detail view of the type-wheel shaft and its connections with the propelling mechanism, together with the unison- 65 ing devices.

In my prior invention, disclosed in the application above referred to, I have described and claimed a novel form of paper-carriage, in which the carriage is fed forward step by 70 step through the agency of an electro-magnet, a rack and pawl, and a retaining-pawl and mechanism for returning the carriage to its normal position during any portion of its journey.

In the present invention I provide a positive power-impelled feed controlled by an electro-magnetic escapement and cause the entire mechanical operation of printing, paper-feed, unisoning, and carriage manipulation to be 80 effected through the agency of power-impelled mechanism which is controlled in its operation by an electro-magnetic escapement. For a full understanding of the invention reference is had to the drawings, in which— 85

A represents the base of the instrument, and B B' B² vertical side frames, either integral therewith or bolted thereto and provided with the necessary brackets for sustaining the operative parts of the mechanism.

T T' are two trains of gear-wheels, the former being impelled by a weight and the latter by a spring-driven drum. The last gear-wheel of the train T meshes with a pinion borne by a shaft journaled in the frame 95 and carrying a gear-wheel J and an escapement f, controlled by a pallet e under the influence of an armature-lever a, borne between two legs of a polarized magnet M, located directly in the main line. The gear-wheel J meshes with a pinion G, adapted to run loosely 100 on a shaft K, journaled in the frame between

the part B and bracket B' and carrying a type-wheel T².

W is a unison-worm having an arm M⁸ and a pin p¹⁰, adapted to fit in a hole in an arm carried by the pinion G, said worm being capable of lateral motion on the shaft K against the stress of the spring s.

U is a unison-lever carried by a shaft M⁶ and having a pin p⁹ on its lower end adapted to take against the arm M when the unison-screw W is carried to the left under the influence of said lever U and as the shaft K is rotated.

Q is an inking-roll carried by the arm R, pivoted to the bracket B³ and provided with a weight W' for holding it in inking contact with the type-wheel T². One shaft of the train of gear T' carries an escapement f', controlled by a two-armed pallet e' on the armature-lever a' of the magnet M', and the last wheel D⁴ of this train is geared to a pinion e², carried by a shaft X, pivoted in the frame B and journaled at its free end to a vertically-moving block F². This shaft X carries a worm u³, adapted to gear with a rack V', secured at its opposite ends to a paper-carriage C C. This paper-carriage is borne in grooved runways G' G² by three frictional rollers c' c² c³ and is provided with paper-guides g' g² at its opposite edges adapted to receive a sheet of paper P². (See Fig. 3.)

The gearing between the shaft which carries the escapement f' and the pinion e², carried by the shaft X, is such that one complete vibration of the armature-lever a', and hence the pallet e', permits one complete rotation of the shaft X, and with it the worm u³, as well as a cam c², located at a point between the pinion e² and the worm. This cam c² is adapted to bear once in each revolution upon an arm N⁵, carried by a rock-shaft M⁶, pivoted in the frame, the said arm N⁵ being returned to its normal position by a spring s⁵ after each action of the cam c². The free end of this arm N⁵ is adapted to bear in its forward movement against the lever V, pivotally secured to the frame B' by rock-shaft V³ at points t² t². On the free end of the lever V is a platen p⁸, adapted to strike against the rear side of the paper and force it against the type-wheel T² when the cam c² forces the arm N⁵ into its forward position.

R² is a rock-shaft parallel with shaft X and pivoted in a frame and a yoke, as shown in Fig. 3. On the outer end of this shaft is an arm c⁴, having a cam-surface adapted to bear against a pin c⁴, fixedly secured to the vertical sliding block F², which carries the free end of the worm-shaft X. The other end of the shaft R² carries an arm c⁴, extending downward and provided with a pin p⁶, adapted to play in a slot s⁶ in the lower end of an arm M⁴, integral with a sliding push-bar M³, which rests at one end upon a pinion j², and is provided with a rack V², meshing therewith. The other end of said push-bar is provided

with a slot s⁵ for sustaining it in a sliding position upon a rod or pin attached to the framework of the machine.

M⁵ is an angular arm rigidly fixed to the push-rod M³ and extending upward and over a pin p⁷ on the unison-arm U, the upper end of said angular arm being provided with a hook, as shown in Fig. 4.

s⁴ is a leaf-spring for restoring the push-bar M³ to its normal position after said push-bar has performed its function.

D' is a drum secured to the frame-work by brackets and provided with a spring on its inner side and a cord c⁴ attached to its surface at one end and to a carriage C C at the other, the function of which is to return the carriage to its normal position, the tension of the spring in the drum being such that when the carriage is released it will be drawn forward in a grooved supporting-frame G' G².

f⁴ is a milled or roughened feeding-roll journaled in the carriage-frame C C and provided with a ratchet r and a propelling-pawl p⁴, secured to a lever D³, which is pivoted to the lower edge of the carriage at p², and is adapted to move laterally in a slotted support G³, secured to the upper edge of the carriage-frame.

D² is a fixed angular arm secured to the frame of the machine and lying in the path of the lever D³, as shown in Figs. 1 and 7.

F²⁰ is a tension-roller pivotally secured to the carriage-frame and held against the paper by spring s², so that as the pawl p⁴ is vibrated the paper will be fed forward. There may be an additional milled roll, the duplicate of f⁴, at the opposite edge of the frame, secured to a shaft extending across said frame, and an additional pressure-roll, if deemed necessary, in order to feed the paper evenly.

I will now describe the electrical connections.

P² P² are the binding-posts for the main-line circuit, and P' P' are similar binding-posts for the local circuit.

l is the main line, coming from the distant transmitter, adapted in this instance to send constantly-recurring currents of opposite polarity. From the binding-posts P² the circuit passes by wire w' to and through the two coils of the polarized magnets M and back again to the binding-post P² and thence to earth at E'.

O is a lever pivotally secured at one end to the frame of the machine and resting at or near its middle with a detent t³ upon a ratchet r³, having as many teeth as there are characters upon the type-wheel or bearing a fixed relation thereto, and adapted when the escapement f is stopped to close the circuit from the local battery BA through the magnet M' and wires w w at the contact-points t t'. The polar magnets M may be replaced by neutral magnets and a transmitter used which constantly interrupts the line-circuit, and thereby imparts motion to the pallet. Any transmit-

ter may be used with this receiver which sends successive impulses constantly to line; but the transmitter which I prefer to use is similar to that disclosed in my prior patents, 5 in which a constantly-operating pole-changer causes a polarized magnet M to act continuously upon the pallet e until prevented by the depression of any key of the transmitter.

I will now proceed to describe the operation 10 of the entire apparatus. As long as the pallet continues to permit the advancement of the escapement-wheel f under the influence of the polar-magnets M the ratchet-wheel r³ continues to lift the circuit-lever O, and therefore 15 to interrupt the local circuit at the points t t'. As this rotation continues the type-wheel shaft K is caused to rotate and a sliding unison-worm W is carried to the left (see Fig. 8) under the influence of a unison-lever U, acting in the worm against the stress of a 20 spring s. This continues until the pin p¹⁰ is released from its engagement with the arm on the pinion G and until the pin p⁹ has come frictionally into contact with the arm M⁸, thereby 25 stopping the type-wheel shaft and permitting the pinion G to run loosely upon the shaft. Suppose now the paper-carriage to be in its 30 normal position with the type-wheel at the extreme left-hand edge of the paper and the transmitter held from action by the last key depressed. The operator on depressing the first key of the transmitter releases it and allows it to run forward until it is stopped by the key last depressed. This permits a specified 35 number of impulses to be sent over the line, and as the unison-lever U was released from the worm W by the last closure of the circuit at t t', as will be described later on, the type-wheel shaft K has again been connected 40 to the pinion G by the arm M and pin p¹⁰ under the influence of the spring s, and hence the type-wheel will be rotated through the desired angle to the letter it is desired to print. When the escapement stops, therefore, 45 the detent t³ of the lever O falls into one of the ratchet-notches of the ratchet r³, allowing the local circuit of battery BA to be closed through the magnet M' and wires w w at the contact-point t t'. This actuates the 50 armature-lever a' and allows the spring-imelled train of gear T' to advance the escapement f' one step, and hence through the agency of gear-wheel D⁴ to propel the pinion e² one half-revolution, thereby causing the 55 shaft X to give to the worm w³ one half-rotation and to advance the rack V' a distance equal to a letter-space. The same action causes the cam c² to impart to the arm N⁵, and hence to the printing-arm V, a forward 60 motion, thereby causing the printing-platen p⁸ to strike the paper in the rear of the particular type it is desired to print. The pallet-lever e' holds the escapement, and hence the pinion e² and shaft X, with its cam c² and printing-lever, in this position until the circuit is broken by again starting the trans-

mitter. Inasmuch as the unison-lever U is fixedly secured to the shaft M⁶, which carries the arm N⁵ each time a letter is printed, this unison-lever will be lifted from the worm W 70 and the type-wheel shaft will be continuously connected with the pinion G, unless the apparatus is allowed to run until the pin p⁹ is locked with the arm M⁸, as before described. The pinion J² (see Fig. 4) is so related in its 75 gearing to that of pinion G on the type-wheel shaft K that the latter will make two complete revolutions while the former is making one, or at least shall make a greater number of revolutions, so that the paper-carriage will 80 not be returned to normal position for less than two rotations of the type-wheel. As the carriage advances under the action of the worm w³, each time a letter is printed the unison-lever U is lifted and carries with it, 85 through the agency of the pin p⁷, the angular arm M⁵, attached to the push-bar M³, thereby lifting the rack V' out of contact with the pinion J² and allowing the spring s⁴ to restore it to normal position. However, should the pinion J² 90 make more than two revolutions undisturbed by the cam c² and the connecting-levers N⁵, U, and M⁵ it will cause the rock-shaft R³ to rotate the cam-arm c³ to its extreme position, as shown in Fig. 6, thereby lifting the block F², 95 and hence the worm w³, out of engagement with the rack V' and permitting the spring-drum D', through the agency of the cord c⁴, to return the paper-carriage to normal position. This action of restoring the paper-carriage 100 to normal position will take place at any time if the escapement-wheel f is allowed to run a sufficient time to permit the pinion J² to make more than two revolutions, and this is accomplished at the transmitter by allowing the pole-changer to transmit the desired 105 number of impulses to the magnets M. When the carriage returns to its normal position after having completed its advance motion, the pivoted lever D³ rides behind the angular lever D² and gives to the free end of said lever, and hence to the pawl p⁴, a forward motion, thereby imparting to the feed-roll f⁴, 110 through the agency of the ratchet r, a forward motion, which advances the paper between said roll and the tension-roll F²⁰ one line, and the apparatus is in a position to print a new line. This operation continues from line to line as the message is printed, and when it is desired to complete a sentence at any portion 115 of a line the mechanism is simply allowed to run, as described, under the influence of the main-line magnets M and the escapement controlled thereby until the worm w³ is lifted out of engagement with the rack V', as already described.

I do not limit myself to the use of the above-described mechanism for printing-telegraphs, as there are features of my invention above described which obviously might give advantageous use in type-writers and analogous printing devices where the paper and paper-

carrying carriage are to be fed and propelled by a source of power controlled by key mechanism, and I desire it to be understood that the claims shall be of such scope as to include 5 inventions of this generic nature. Nor do I limit myself to the use of two sources of constantly-applied power, as it is obvious the entire mechanism might be propelled from a single source of power, as a spring-drum or 10 weight acting through a train of gear.

Having thus described my invention, what I claim, and desire to secure by Letters Patent of the United States, is—

1. A printing-telegraph receiver of the page 15 type, having a type-wheel carried by a rotary shaft connected through a sliding unison worm and pin with a loose-running gear-wheel which meshes with a power-impelled train of gear, and a paper-carriage geared to a 20 second source of power, in combination, with escapements and mechanical connections, as described, whereby the carriage is moved athwart the type-wheel, printing effected, and the paper advanced line by line, substantially 25 as described.

2. In a printing-telegraph receiver or analogous printing device, a type-wheel carried by a rotary shaft geared to a continuously-acting source of power, a paper-carriage 30 geared to a second continuously-acting source of power, escapements for the type-wheel and paper-carriage, a printing-platen carried by a printing-lever mechanically connected to the second source of power, and mechanical and 35 electrical connections whereby printing is effected in page form, substantially as described.

3. In a printing-telegraph receiver or analogous printing device, a type-wheel and paper- 40 carriage and an actuating-motor provided with an escapement for operating each, a retractor for moving the said paper-carriage backward, feed mechanism for advancing the paper line by line, and mechanical connections 45 between the type-wheel and paper-carriage for releasing the paper-carriage at any point in its forward movement, substantially as described.

4. In a printing-telegraph receiver or analogous printing device, a type-wheel carried by a rotary shaft geared to a continuously-acting source of mechanical power, a paper-carriage geared to a second continuously-acting source of power, a printing-platen carried 55 by a lever having mechanical connections with the second source of power, and an escapement for each source of power, substantially as described.

5. A printing-instrument having a rotary 60 type-wheel, a printing-platen carried by a printing-lever, a paper-carriage, and power impelling mechanism geared to a rack and worm-shaft, in combination with mechanical connections between said parts and the power 65 impelling mechanism whereby the paper-carriage is moved, the paper fed, and printing

effected by the power derived from said impelling mechanism, substantially as described.

6. A printing-instrument having a type-wheel, a printing-platen carried by a printing-lever, a paper-carriage, power impelling mechanism geared to a rack-and-worm shaft and having mechanical connections intermediate the paper-carriage, the printing-lever, and the type-wheel, in combination with escapement 75 mechanism for regulating the application of the power whereby printing is effected, the paper-carriage advanced step by step, and the paper fed forward line by line, substantially as described.

7. In a printing telegraphic receiver, a type-wheel borne by a shaft carrying a loose-running pinion meshing with a train of gear, a spring-pressed worm and unison-lever, and connections whereby the shaft and gear-train 85 are connected and disconnected at will, substantially as described.

8. In a printing-telegraph receiver or analogous printing-instrument, a paper-carriage positively connected to a power-impelled train 90 of gear through a rack-and-worm gear, in combination with mechanism for releasing the worm from the rack at any part of its journey, said releasing mechanism consisting of a cam-lever and rock-shaft, and mechanical 95 connections with a power-impelled train of gear, as described, additional means being provided for returning the carriage to normal condition when released, all of said parts being regulated in their operation by an escapement, substantially as described.

9. In a printing telegraphic receiver or analogous printing-instrument of the page type, a paper-carriage having a rack connected by worm-gear and shafting to a source of 105 power, a spring-impelled drum connected to the carriage for restoring it to normal position, ratchet-and-pawl feeding mechanism connected to the carriage and frame, and releasing mechanism consisting of a rock-shaft, 110 cam-lever, and mechanical connections operatively connected with the worm-gear and the source of power, all substantially as described.

10. In a printing-telegraph receiver, a type-wheel geared to a constantly-acting source of 115 power, a paper-carriage geared to a second constantly-acting source of power, and a printing-platen carried by a printing-lever mechanically connected to the latter source of power, in combination with a pair of electro-magnetic escapements, the former controlled by an electro-magnet in the main line and the latter by a second electro-magnet in a local circuit, and electrical connections, substantially as described.

11. In a printing telegraphic receiver, a power-impelled type-wheel, a power-impelled paper-carriage, an escapement controlled by line-currents for regulating the rotation of the type-wheel, and a second escapement controlled by a local circuit connected to a mechanical circuit-closer actuated by the first 125

escapement for regulating the advancement of the carriage, substantially as described.

12. In a printing-telegraph, the combination of the following elements: a power-impelled type-wheel, an escapement therefor, a power-impelled carriage, an additional escapement therefor, a unisoning device for connecting at

will the type-wheel to the shaft which carries it, and mechanical connections, substantially as described.
